US0D1044756S

(12) **United States Design Patent** (10) **Patent No.:** **US D1,044,756 S**
(45) **Date of Patent:** **** Oct. 1, 2024**

(54) **RFID READER**

(71) Applicant: **Crestron Electronics, Inc.**, Rockleigh, NJ (US)

(72) Inventors: **Howard Balch**, Bloomingdale, NJ (US); **Donald Florcak**, Tenafly, NJ (US); **Sae Jhun**, Bayside, NY (US)

(73) Assignee: **Crestron Electronics, Inc.**, Rockleigh, NJ (US)

(**) Term: **15 Years**

(21) Appl. No.: **29/800,258**

(22) Filed: **Jul. 20, 2021**

(51) LOC (14) Cl. **14-03**

(52) U.S. Cl.

USPC **D14/155**

(58) **Field of Classification Search**

USPC D14/356-358, 383-385, 420, 421, 453, D14/454, 217, 253, 299; D13/108, 147,

D13/168

CPC G06Q 20/347; G06Q 20/322; G06Q 40/02

(57) **CLAIM**

The ornamental design for an RFID reader, as shown and described.

DESCRIPTION

FIG. 1 shows a front perspective view of an RFID reader according to an embodiment;

FIG. 2 shows a front perspective view thereof attached to a touchscreen;

FIG. 3 shows a front elevation view thereof;

FIG. 4 shows a rear elevation view thereof;

FIG. 5 shows a left elevation view thereof;

FIG. 6 shows a right elevation view thereof;

FIG. 7 shows a right elevation view thereof attached to a touchscreen;

FIG. 8 shows a top plan view thereof; and,

FIG. 9 shows a bottom plan view thereof.

The broken line showing of the touchscreen is included for the purpose of illustrating environment and forms no part of the claimed design.

1 Claim, 5 Drawing Sheets
